UNITED STATES PATENT OFFICE

164,498

REFRIGERATED BEVERAGE DISPENSER

Robert R. Hull, Pasadena, Calif., assignor to California Fruit Growers Exchange, Los Angeles, Calif., a corporation of California

Application August 22, 1949, Serial No. 4,649

Term of patent 14 years

(Cl. D2—3)

To all whom it may concern:

Be it known that I, Robert R. Hull, a citizen of the United States, residing at Pasadena, State of California, have invented a new, original, and ornamental Design for a Refrigerated Beverage Dispenser, of which the following is a specification, reference being had to the accompanying drawing, forming a part hereof.

I claim:

The ornamental design for a refrigerated beverage dispenser, as shown.

ROBERT R. HULL.
